UNITED STATES PATENT OFFICE.

WILLIAM BERRY AND GEORGE W. POST, OF FOND DU LAC, WISCONSIN.

RAIL-CLAMP.

966,989.

Specification of Letters Patent. Patented Aug. 9, 1910.

Application filed April 1, 1910. Serial No. 552,782.

To all whom it may concern:

Be it known that we, WILLIAM BERRY and GEORGE W. POST, citizens of the United States, residing at Fond du Lac, in the county of Fond du Lac and State of Wisconsin, have invented certain new and useful Improvements in Rail-Clamps; and we do hereby declare the following to be a full, clear, and exact description of the invention, such as will enable others skilled in the art to which it appertains to make and use the same.

Our invention relates to rail clamps intended to serve as safety devices to prevent the rails from tipping, spreading or creeping, but which do not take the place of the ordinary spikes for securing said rails to the ties.

One of the objects of our invention is to provide a clamp of this kind which is adjustable to fit different sizes of rails.

Another object is to improve the construction and arrangement of the fastening device for holding the adjustable jaw.

Still another and important object is to provide for the automatic depression of the clamp as the top of the tie wears away or the rail is driven down into the tie, whereby the clamp is at each level parallel with its initial position. In other words, our clamp is adapted to automatically adjust itself to the thickness of the tie, or the thickness of the portion of the tie below the rail, so that it always supports the rail in its proper upright position.

The general type of this clamp is similar to that shown and described in the pending application of William Berry, filed November 6, 1909, Serial No. 526,608, in that it has the same lever extension, which, acting together with the jaw bearing down upon the inner edge of the rail foot and the outer jaw which also supports the outer edge of said rail-foot, serves to effectually prevent the rail from tipping outwardly. In our present invention, however, we have made one of the jaws adjustable and removable for the purpose already explained. This renders it unnecessary to use the inclined-bottomed opening between the jaws. The base of the opening in our present invention is straight and engages the full under surface of the foot of the rail.

The clamp is preferably made in skeleton form with laterally projecting ribs of any suitable contour. Portions of these ribs

form a pocket housing the end of the bolt and the nut which secure the movable jaw in place. The end of the lever extension is provided with a self-adjusting fastening 60 which permits the clamp to drop parallel with the top of the tie, for the purpose already explained.

The invention also consists in the features of construction and combinations of parts 65 hereinabove described and specified in the claims.

In the accompanying drawings: Figure 1 is a plan view of a tie and a rail showing one of our clamps as applied in use. Fig. 2 is 70 a side view of the tie and clamp, the rail being shown in section. Fig. 3 is a section on the line $x-x$ of Fig. 2. Fig. 4 is a section on the line $y-y$ of Fig. 2. Fig. 5 is a broken detailed view of the end of the lever 75 extension of the clamp with the spring plate removed. Fig. 6 is a detailed view of the spring plate, and Fig. 7 is a view similar to Fig. 2, but showing a modified form of the clamp, the inner jaw of which is adjustable. 80

Referring more particularly to the drawings, 1 designates the rail and 2 the tie. The clamp may be said to comprise the body portion 3, the lever extension 4, and the inner and outer jaws 5 and 6, respectively. As 85 illustrated in Figs. 1 and 2, the inner jaw 5 is made integral with the clamp, while the outer jaw is adjustable to accommodate different sizes of rails. The rail illustrated is of medium size, it being understood that the 90 clamp may be used on smaller as well as larger ones.

The base 7 of the opening or space between the jaws has a projection 8 extending beyond the movable jaw, as here shown, so 95 that a larger rail with a broader foot may be inserted without having its foot extend beyond said projection. Said removable jaw is secured to the clamp by means of a bolt 9 having its head 10 arranged at the 100 outside and its threaded end inserted through the end rib 11 into a pocket or housing 12 formed by other ribs 13. The nut 14 on the inner end of the bolt is protected in this pocket from any external object which might tend to loosen it. 105

When the medium size rail is used, a washer 15, of suitable thickness, is placed between the shank of the adjustable jaw and the end rib 11. This gives a bearing for 110 said jaw to rest against and prevents it from tipping outwardly. Additional washers, or

a single thicker washer, may be employed when the clamp is used on a larger rail. In the case of a smaller rail, the washer may be removed, if necessary, thereby bringing the shank of the jaw to bear directly upon the end rib 11.

The end of the lever extension has formed therein an elongated vertical slot 16. Near each end of said slot there are formed a series of horizontal notches or serrations 17. These notches are ratchet-shaped, the upper face of each being squared, while its lower face is beveled, as illustrated in Fig. 4. A spring plate 18 is fitted over the slot 16 and is provided with turned ends 19 which engage the serrations 17. Said spring plate has a round opening 20 to fit the shank of the bolt or spike 21 which secures the lever extension to the side of the tie. When the clamp is first adjusted, the bolt or spike is placed at the lower end of the slot 16 where it will exert the downward pressure upon the clamp which gives the proper lever action for supporting the rail. The placing of the spike at this point also allows for the clamp to be depressed to a lower level parallel to its initial position if the top of the tie wears off or the rail is driven into the tie below its surface. Each time the clamp is depressed in this manner, one of the serrations or notches 17 slips down below the turned ends of the spring plate which then snap into place in the next notch and by engagement with the squared upper side of the serrations support the clamp in position to give the proper lever action to the same advantage as when the securing spike engages the bottom of the slot 16.

In the modification illustrated in Fig. 7, 40 the inner jaw 22 is adjustable, the outer one 23 being made integral. The bolt 24 which holds the inner jaw in place has its threaded end and nut housed in a pocket 25 formed by laterally extending ribs 26 on the clamp. 45 The lever extension 28 is straight at the top and forms a bearing for a lug or projection 27 on the movable jaw. The same form of automatically adjustable fastening for the end of the lever extension is here used, 50 as on the preferred form.

We claim:

1. A rail clamp of the character described, having inner and outer jaws for engaging the foot of a rail, and means for securing

said clamp to the side of a tie, said fastening means being automatically adjustable to permit the clamp to be depressed parallel to its initial position for the purpose specified.

2. A rail clamp of the character described, having inner and outer jaws adapted to engage the foot of a rail, a lever extension, and means for securing the end of said extension to the side of a tie, said fastening means being automatically adjustable to permit the clamp to be depressed parallel to its initial position for the purpose specified.

3. A rail clamp of the character described, having inner and outer jaws for engaging the foot of a rail, and a vertical elongated slot, horizontal serrations at the opposite ends of said slot, a spring plate having its ends turned inward to engage said serrations and provided with a round opening through its center, and a securing bolt fitted in the opening in said spring plate and passed through the slot in the clamp whereby said spring is retained with its turned ends in engagement with said serrations for the purpose specified.

4. A rail clamp of the character described, having inner and outer jaws for engaging the foot of a rail, and a vertical elongated slot, horizontal serrations at the opposite ends of said slot, said serrations having their lower faces beveled and their upper faces squared, a spring plate having its ends turned inward to engage said serrations and provided with a round opening through its center, and a securing bolt fitted in the opening in said spring plate and passed through the slot in the clamp whereby said spring is retained with its turned ends in engagement with said serrations for the purpose specified.

5. A rail clamp of the character described, having an outer rigid jaw, an inward lever extension, an adjustable inner jaw adapted to slide on said lever extension, means to secure said adjustable jaw in place which is housed in a pocket in the clamp, and means to secure said lever extension to the side of a tie.

In testimony whereof, we affix our signatures in presence of two witnesses.

WILLIAM BERRY.
